UNITED STATES PATENT OFFICE.

JOHN B. WARING, OF NEW YORK, N. Y.

PULVERIZING-MACHINE.

SPECIFICATION forming part of Letters Patent No. 357,434, dated February 8, 1887.

Application filed September 28, 1885. Serial No. 178,342 (No model.)

To all whom it may concern:

Be it known that I, JOHN B. WARING, of New York, in the county of New York and State of New York, have invented a certain Improvement in Pulverizing-Machines, of which the following is a specification.

My present improvement is especially intended for use in pulverizing material in a wet state. It is also particularly applicable in many respects to the concentration and amalgamation of precious metals set free by pulverizing material containing the same.

I will describe a machine embodying my improvement, and then point out the various features of the improvement in the claims.

The accompanying drawings illustrate a machine embodying my improvement.

Figure 1 is a vertical section of a machine, taken in a plane coincident with the center of shaft, but showing the shaft and certain other parts unsectioned. Fig. 2 is a section of the machine, taken at the plane of the dotted line $x-x$ of Fig. 1. Fig. 3 is a section of the machine, taken at the plane of the dotted line $y-y$, Fig. 1. Fig. 4 is a transverse section of the chamber on a smaller scale, illustrating certain parts more fully than they are shown in the other figures. Fig. 5 is a detail view showing the arrangement of certain guides employed in the machine. Fig. 6 is a side view, and Fig. 7 a sectional view, of a certain scoop employed therein. Figs. 8, 9, and 10 are detail views showing the arrangement of certain propelling-blades.

Similar letters of reference designate corresponding parts in all the figures.

A designates a chamber, consisting, as here shown, of a circular body-piece, a , and two heads, a' a'' . Bolts a^3 , passing through the edge portions of the heads a' a'' and the body-piece a , secure these parts together. The interior surface of the body-piece a is provided with a groove or rabbet, a^4 , which preferably flares or increases diametrically toward the outer edge. In this rabbet is fitted a ring of steel, a^5 , which externally flares toward one edge, so as to correspond with the rabbet, and internally is flat from edge to edge, or approximately so. This ring a^5 fits snugly in the rabbet, and is held between the inner edge of the rabbet and a circular rib, a^6 , which projects from the head a' . The bolts a^3 not only secure

the heads a' a'' and body-piece a together, but they also serve to secure the ring a^5 in place. The head a' is shown as quite flat, except near the outer edge, where it is rounded inward toward the ring a^5 . At the center of this head a' is an outwardly-tapering tubular portion, a^7 , through which the material to be pulverized enters the chamber. From the tapering portion a^7 a tube or hopper-chute, a^8 , extends to a hopper whence the material to be pulverized is fed to the chamber. The head a'' is approximately flat, but near the edge curves slightly inward, meeting thereby a portion, a^9 , of the body-piece a , that curves transversely inward to the inner end of its rabbet a^4 , and forms what may be termed a "gutter." This head a'' has a central outwardly-extending tubular portion, a^{10} . All parts of the chamber, except the ring a^5 , may be made of cast-iron.

The chamber A is intended to rotate; hence the tubular portions a^7 a^{10} of the heads a' a'' are externally cylindrical to serve as trunnions, 75 and are supported in bearings a^{11} , comprised in standards a^{12} . The standards a^{12} are shown as mounted upon supports a^{13} a^{14} , which are made in the form of boxes, and secured thereto by bolts or screws. These box-like supports 70 may be made of cast-iron.

The exterior of the body-piece a of the chamber A is adapted to receive a belt, G, which also passes around a pulley, H, on a rotary shaft, H', which is journaled in any suitable 85 bearings and driven by any desirable motor. The chamber A and the shaft H' rotate in the direction indicated by the arrows which are adjacent to them. The tube or hopper-chute a^8 does not rotate with the chamber. It is 90 here shown as formed in one casting with a water-inlet, a^{15} . This whole casting is mounted upon and secured to the box-like support a^{13} .

In the chamber A are pulverizing-rollers B, which travel in close proximity with the interior surface of the ring a^5 . These rollers, as here shown, are propelled by rollers C. I have shown three of the rollers B and a corresponding number of the rollers C. I do not, however, wish to be confined to any particular number. A carrier, D, is combined with the rollers B C and affixed to a shaft, E, so as to be carried around by the latter. It may be keyed or similarly fastened to the shaft and

collars a^{20} a^{21} , secured by screws to the shaft E, prevent any movement of it lengthwise of the shaft. The motion of the carrier causes the rollers B C to revolve within the chamber.

5 As the rollers B C revolve within the chamber they rotate on their axes.

The carrier D consists, essentially, of two plate-like portions, d^1 and d^2 , and an intermediate hub-like portion, d^3 . It may also comprise connecting portions d^4 . It can be made of cast-iron in one piece. The plate-like portion d of the carrier is shown as made in the form of a circular disk; but the plate-like portion d^3 is of somewhat irregular form, consisting, 15 essentially, of a central portion and three arm-like portions extending therefrom.

The propelling-rollers C are arranged upon shafts c , which are supported by the carrier. In the example of my improvement which I 20 have shown these shafts c are not intended to rotate within their bearings in the carrier, but the rollers C are intended to rotate upon these shafts. The rollers B are pulverizing-rollers. They have no shafts. The propelling-rollers C, during the rotation of the shaft 25 E, force the pulverizing-rollers B around the chamber. As soon as the pulverizing-rollers acquire sufficient centrifugal force they fly out close to the interior surface of the ring a^5 , and 30 thereafter they travel around the same.

In traveling around the chamber A the pulverizing-rollers B acquire a rotary motion and cause the propelling-rollers C also to rotate. The revolution of the rollers C of course tends 35 to cause an outward movement of them through centrifugal force. This tendency is, however, more or less neutralized by the manner in which the said rollers C are rotated by the rollers B, because the latter act on them at 40 such a point as to tend to force them toward the axis of the shaft E.

Both the rollers B and C may advantageously be made of steel. When the portions d^3 of the carrier are used, they will preferably 45 be made arc-shaped, and arranged so that their concave sides will be toward the pulverizing-rollers B. They form guards and prevent the pulverizing-rollers from dropping down beyond the control of the propelling-rollers C when the motion of the carrier ceases. The shaft E extends through the chamber A and the tubular portions a^7 a^{10} of the latter. Where it passes through the tubular portion a^7 , a sleeve, a^{16} , extends inwardly from 50 the tubular portion a^7 to the collar a^{20} .

The shaft E is supported in bearings e , comprised in standards e' , erected on the base-pieces a^{13} a^{14} .

On the shaft H' pulleys H^2 are affixed. Belts 60 I pass around the pulleys H^2 , and also around pulleys I' affixed to the shaft E. The shaft E is thus rotated in such direction as to cause the carrier D to revolve in the direction indicated by the arrow which is adjacent to it.

65 The motion imparted by the belts I to the carrier D is faster than the motion which the

chamber A derives from the belt G. The tendency of the chamber to acquire additional speed from the rollers B is resisted by the belt G. This does not involve a waste of power, 70 however, because any power of rotation which the chamber thus transmits to the shaft H' aids in rotating the shaft. The speed of the chamber may be varied by selecting a pulley, H^2 , of proper size.

In the lower part of the tube or hopper-chute a^8 , and extending around the sleeve a^{16} , are guides a^{17} , which will direct material that is introduced through the hopper-chute into the chamber A beyond the fluid-inlet a^{15} . 75 These guides, as here shown, consist of a plate. The top of the sleeve a^{16} , to the rear of this plate, is flat and covers the space back of the plate and above the tube.

The shaft E has connected to one end, by a suitable union-coupling, E', a non-rotary water-pipe, E^2 , and the shaft is hollow from the end which is connected to the said water-pipe to about the middle of its length, so that water may flow into it from said pipe.

A branch water-pipe, E^3 , is connected to the water-pipe E^2 , and also to a nipple which communicates with a water-conduit, a^{22} , which is formed in the support a^{13} . The water-inlet a^{15} is in communication with the water-conduit a^{22} , and from the latter water can pass to the water-inlet a^{15} . A packing, a^{23} , consisting of a piece of flexible tubing fitted into flaring recesses in the top of the support a^{13} and at the bottom of the water-inlet a^{15} , makes a tight joint between the parts.

The water-pipe E^3 is shown as provided with a cock for controlling the passage of water through it. The flow of water through the pipe E^3 may be similarly controlled. The water which passes through the water-inlet a^{15} enters the tubular portion a^7 of the chamber A close to where the material to be pulverized is introduced, and it prevents said material from adhering. Passing beyond the tubular portion a^7 of the chamber A, the material and water fly out toward the circumferential portion of the chamber. The material will accumulate there to a thickness which will make it coincident with the inner surface of the ring a^5 115 and substantially to the line a^{25} , Fig. 1.

The circumferential portion of the chamber is provided internally with a number of lugs, a^{36} , extending toward the center of the chamber. They cause the material to be pulverized 120 to revolve with a speed corresponding to that of the chamber.

The material to be pulverized is reduced principally between the pulverizing-rollers B and the ring a^5 , but also more or less between the pulverizing-rollers and the propelling-rollers C. It may be aided in its passage between the pulverizing-rollers and the rings by oblique propelling-blades p^{10} , arranged on the edge of the plate-like portion d of the carrier 125 D. The form of the propelling-blades and their arrangement are shown more clearly in

Figs. 8, 9, and 10. The water flowing into the shaft E passes out through radial holes e^3 into ports or passages d^4 , extending radially within the plate-like portion d of the carrier D. From 5 the passages d^4 it passes into cavities in the shafts e and escapes from radial extensions of these cavities into cavities e' in the central portions of the rollers C. The water reaching the rollers C passes away between these 10 rollers and their shafts, and flowing out at both ends of the rollers C not only lubricates the shafts, but prevents the admission of grit.

A disk, F, which may advantageously be made of steel, is fastened to the carrier D close 15 to the plate-like portion d . It is shown as secured in place by the collar a^{21} , and extends to within a short distance of the interior of the chamber A. An annular piece or ring, J, which may also be advantageously made of 20 steel, is arranged close to the disk F, but is farther than it from the carrier D. This ring J is fastened to lugs a^{24} (here shown as six in number) extending from the interior of the chamber. Its outer edge is closer to the interior 25 of the chamber than is the outer edge of the disk F. The ring overlaps the disk F but slightly. The space between the ring and disk is very small.

The lugs a^{24} may be cast integral with the 30 chamber A. They have notches in which the ring fits and is held. The ring is made of two semicircular portions. One section is slipped into its place within the notches of three of the lugs a^{24} . Then the other section is inserted 35 into the notches of the three other lugs a^{24} . It will be necessary to spring or bend both sections somewhat laterally to get the last-inserted section into its place. When the last-inserted section is in place, its ends abut against 40 the ends of its fellow. Then both sections are turned around until their ends are within opposite lugs a^{24} . The ends of the sections will thereupon be prevented from passing one another, and the sections will be secured in place. 45 This may be best understood by reference to Fig. 4.

Mercury may, when desirable, be used in the gutter a^9 of the chamber A in sufficient quantity to almost reach to outer edge of the 50 ring J when distributed around the gutter by centrifugal force generated by its rotation with the chamber.

Pulverized material passing beyond the ring a^5 is caused by the high velocity of the disk F to be thrown outward with great force into it and to pass over the surface of the mercury, and any valuable metal which may be comprised in it will thus be thrown into the mercury and amalgamated or concentrated on its surface. 55 The lugs a^{24} prevent the material contained in the gutter outside of the ring J from revolving faster than the chamber, but cause the same to revolve with the chamber. The ring J separates the material that has passed under 60 it from that which is being pulverized and is in a state of violent agitation; hence the ma-

terial which has passed under the ring J is allowed to remain in a state of rest, except for its revolution with the chamber.

Water in the chamber may pass between the 70 disk F and ring J and into the gutter a^9 inward of the mercury, or, in other words, nearer the center of the chamber, thereby causing a sufficient disturbance of the mercury to insure amalgamation where amalgamation is possible. 75

It will be desirable in many instances to provide for violently agitating the matter which passes the ring a^5 . For this purpose I arrange within the chamber A a scoop, K. (Shown more clearly in Figs. 6 and 7.) This scoop is hung 80 at the upper end on a pivot, a^{26} , which is supported upon an arm extending from a tubular portion of a clamp, K', that embraces an outer annular projection on the standards a^{12} , and may be fastened in different positions on such 85 annular projection by a set-screw, k. The pivot a^{26} may be inserted in any one of a number of holes, k' , with which the scoop K is provided near its upper edge. The lower end of the scoop K is pivotally connected to one end of 90 a link, K², which at the other end is pivotally connected to an arm, t, which is affixed to a rock-shaft, L. The rock-shaft L is journaled in the clamp K' and extends through the tubular portion thereof, from which extends the 95 arm supporting the pivot a^{26} . The rock-shaft L has affixed to it another arm, t'. This arm t' may be fastened in any desirable position by means of a pin, t², which passes through it and enters one of a series of holes, t³, which 100 are arranged in the arc of a circle in the clamp K'. By shifting the rock-shaft the lower end of the scoop may be moved farther from or nearer to the interior of the chamber A. In the scoop, preferably, are slots k^1 k^2 , the lower 105 edges of which may be bent or extended inward. The upper edge of the scoop catches the matter which is close to the interior of the chamber, or, in other words, farthest from the center of the chamber, and removes it therefrom. Some of the matter escapes from the 110 scoop through the slots of the scoop, and the remainder passes off the lower end of the scoop. The matter is thus frequently put into a state of commotion and perfect concentration and 115 amalgamation are facilitated.

In Fig. 3 the scoop is shown as supported in a different position on the annular ring from that shown in Fig. 6, in order to conduce to a clear illustration of the parts shown in Fig. 3. 120

M is a pipe extending into the chamber A close to the ring J. Its upper end is turned so that it may catch the matter which rotates with the chamber A. It is supported by a standard, a^{27} , which is erected upon the support a^{14} , and provided with a vertical slot, a^{28} , through which passes a screw, a^{29} , fastened to the pipe. A nut, a^{30} , applied to the screw a^{29} outside the standard a^{27} , provides for clamping the pipe in different vertical positions. 125 When only the water and waste matter are to be removed, the pipe is lowered; but when con-

centrated material is to be taken off the tube is elevated more. The position of the tube regulates the depth or thickness of the layer or stratum of water and pulverized material.

5. The matter taken off by the pipe M is delivered into a chute, m, arranged in the support a¹⁴. The chute m has pivotally attached to it a swinging section, m', that works over flanges arranged at the lower end of the chute 10 m, and made concentric with the pivots on which the said section m' swings. A rod, M², pivotally connected to the section m', provides for swinging the said section into communication with a delivery-chute, N², in a base-piece, N', designed to carry off the water and waste matter, or after the valuable material has been concentrated or amalgated, into communication 15 with a chute, N, in said base-piece, designed to carry away such concentrated or amalgamated material, the pipe M having been properly adjusted for removing such material 20 from the chamber A. The base-piece N' has the supports a¹³ a¹⁴ mounted upon it, and it may be made of cast-iron.

25. In the base-piece N' below the chamber A is a tray, n, which inclines in both directions toward one corner. The body-piece a of the chamber A is provided with a removable screw-plug, a²¹. This plug may be removed 30 when that portion of the chamber A containing it is immediately above the tray n to allow the mercury, with the concentrated and amalgamated material, to pass out.

The use of the water may be omitted at 35 times, or altogether, if desirable. Instead of water, oils or chemically-prepared liquids may be used. Where dry products are desired, air or other gas may be circulated, instead of liquid, through the machine.

40. What I claim as my invention, and desire to secure by Letters Patent, is—

1. The combination, with the body a, made in one integral piece and provided with the rabbit a⁴, of the head a², the head a', provided 45 with the circular rib a⁶, the bolts a³, and the ring a⁵, substantially as specified.

2. In a pulverizing-machine, the combination, with a pulverizing-chamber, of rollers, a carrier supporting the rollers, and provided 50 with passages for conveying fluid to the rollers, and a shaft having the carrier mounted upon it, and a passage leading to the said passages of the carrier, substantially as specified.

3. In a pulverizing-machine, the combination, with a pulverizing-chamber, of rollers,

non-rotary shafts supporting the rollers and having fluid-passages leading to chambers arranged between the ends, a carrier receiving the said shafts and provided with passages leading to the passages of the said shafts, and 60 a main shaft supporting the carrier and provided with a fluid-passage leading to the passages of the carrier, substantially as specified.

4. In a pulverizing-machine, the combination, with a rotary chamber, of a stationary 65 pipe extending into the chamber, a support for said pipe, with which said pipe is adjustably connected, so as to be capable of independent adjustment transversely to the axis of the chamber, an intermediate stationary chute 70 communicating with said pipe and having a swinging section pivotally connected thereto, and two outlet-chutes, with either of which the swinging section may be made to communicate, substantially as specified. 75

5. In a pulverizing-machine, the combination, with a chamber having an inlet, a⁷, for material to be pulverized, of a fluid-inlet, a¹⁵, and guides a¹⁷, arranged in the inlet a⁷ and extending beyond the outlet of the fluid-inlet a¹⁵, 80 substantially as specified.

6. In a pulverizing-machine, the combination of a chamber provided with a gutter, a⁹, rollers operating in conjunction with the chamber, a carrier for the rollers, and a disk, F, 85 affixed to the carrier and extending close to the gutter and beyond the surface of the grinding-ring, substantially as specified.

7. In a pulverizing-machine, the combination of a chamber, rollers operating therewith, a carrier for the rollers, the disk F affixed to the carrier, and an annular piece or a ring affixed to the chamber in close proximity to the said disk, substantially as specified. 90

8. In a pulverizing-machine, the combination of a rotary chamber and a scoop provided with openings and serving to agitate the contents of the chamber, substantially as specified. 95

9. In a pulverizing-machine, the combination, with the pulverizing-rollers B, their carrier, and the ring a⁶, of the propelling-blades p¹⁰, arranged on the plate-like portion d of the carrier D, obliquely to the plane of rotation of the carrier, substantially as specified. 100
